(57) **CLAIM**

The ornamental design for a scaffold trestle leg, as shown and described.

DESCRIPTION

FIG. 1 is a perspective view of the scaffold trestle leg showing my new design;

FIG. 2 is a front view of the scaffold trestle leg shown in FIG. 1;

FIG. 3 is a left side view of the scaffold trestle leg shown in FIG. 1;

FIG. 4 is a back side view of the scaffold trestle leg shown in FIG. 1;

FIG. 5 is a right side view of the scaffold trestle leg shown in FIG. 1;

FIG. 6 is a top plan view of the scaffold trestle leg of FIG. 1 shown in a larger scale; and,

FIG. 7 is a bottom plan view of the scaffold trestle leg of FIG. 1 shown in a larger scale.

The broken lines in the figures are for the purpose of illustrating portions of the scaffold trestle leg and form no part of the claimed design.
